(57) **CLAIM**

The ornamental design for a chair, as shown and described.

DESCRIPTION

FIG. 1 shows a front perspective view of a chair according to the present invention.

FIG. 2 shows a rear perspective view of the chair of FIG. 1.

FIG. 3 shows a first side view of the chair of FIG. 1.

FIG. 4 shows an opposite side view of the chair of FIG. 1.

FIG. 5 shows a front view of the chair of FIG. 1.

FIG. 6 shows a rear view of the chair of FIG. 1.

FIG. 7 shows a top view of the chair of FIG. 1.

FIG. 8 shows a bottom view of the chair of FIG. 1. No claim is made to the bottom view of the chair.

FIG. 9 shows a side view similar to the view of FIG. 3, with a user seated on the chair; and,

FIG. 10 shows a side view similar to the view of FIG. 9, with a user extending their back rearwardly.

Any broken lines shown are directed to portions of the chair which are not claimed.

1 Claim, 9 Drawing Sheets
